DESIGN FOR A GOGGLE

Lawrence A. Severy, Southbridge, Mass., assignor
to American Optical Company, Southbridge,
Mass., a voluntary association of Massachusetts

Application December 31, 1942, Serial No. 109,173

Term of patent 14 years

To all whom it may concern:

Be it known that I, Lawrence A. Severy, a citizen of the United States, residing at Southbridge, in the county of Worcester and State of Massachusetts, have invented a new, original, and ornamental design for Goggles, of which the following is a specification, reference being made to the accompanying drawing, forming a part thereof.

Fig. 1 is a front perspective view of a goggle showing my new design, the essential features of which are shown in full lines,

Fig. 2 is a fragmentary rear perspective view of said goggle; and

Fig. 3 is a top plan view thereof.

The temples have been shown fragmentarily in Figs. 2 and 3 for convenience of illustration.

I claim:

The ornamental design for a goggle, substantially as shown and described.

LAWRENCE A. SEVERY.
